CUFF LINKS

Abraham Blumstein, 9803 69th Ave., Forest Hills, N.Y.
Filed Feb. 12, 1964, Ser. No. 344,350
6 Claims. (Cl. 24—97)

This invention relates generally to cuff links and more particularly to cuff links of the pivoted toggle variety and forms a continuation-in-part of my copending application filed on November 15, 1963, Serial No. 324,067, entitled Cuff Links.

One object of this invention is to provide a toggle type cuff link assembly having a toggle finding for a jewel which is simple in construction, and which may be manufactured in large quantities at a relatively low cost.

Another object of this invention is to provide a toggle cuff link assembly which may easily and quickly be assembled.

The preferred embodiment of the present invention comprises a hollow shell having a peripheral wall and an open top. The peripheral wall includes opposed longitudinally extending side walls having respective rectangular slots extending to the bottom edge of the peripheral wall.

As an important feature of the present invention, the spacing between the upper portion of the opposed side walls is greater than the spacing between the lower portion of the side walls in any one vertical plane thereby defining a shelf spaced from the top of the peripheral wall and extending inwardly, circumferentially about the inner surface thereof. The shelf is adapted to receive the bottom surface of a jewel in abutting relation thereon. A longitudinally extending flexible and resilient blade spring is received within the shell below the shelf and the top of the respective slots and has an aperture at each end thereof.

The present invention also comprises a yoke having a pair of spaced legs connected by a crossbar, which is square in cross-section, at one end. This crossbar is positioned within the slots. A longitudinally extending head is fixed to the other end of the yoke. The shell further includes a bottom closure having a longitudinally extending opening therein. The ends of the blade spring extend past the edges of the opening and the apertures in the blade spring are positioned to overlie the respective ends of the opening. A bottom closure strip, made of thin brass or the like, underlies the crossbar and closes the bottom of the shell; said strip having tabs at each end thereof which pass upwardly through the apertures in the blade spring and are bent over said spring. Additionally, the ends of the shell may be swaged over the ends of the blade spring to firmly maintain the spring in position. Thus, the crossbar is clamped frictionally between the closure strip and the blade spring. Hence, by the application of appropriate force, the shell may be turned between a position in which it is aligned with the yoke (for inspection into a cuff) and the position in which it is perpendicular to the yoke (to hold the cuff link in place on the cuff between the toggle head and the fixed head). The blade spring and, to a lesser extent, the closure strip serve as yieldable members to permit this action of the shell.

The above and other objects and features of the present invention will become more apparent from a consideration of the following detailed description when taken in conjunction with the drawings in which:

FIG. 1 is a perspective view of a toggle bar cuff link made in accordance with the present invention illustrating the position of the parts of the cuff link when it is mounted in a cuff;

FIG. 2 is an enlarged exploded perspective view of the toggle head operating assembly of the cuff link shown in

2

FIG. 1 with a portion of the shell broken away;

FIG. 3 is a cross-sectional view taken along the line 3—3 of FIG. 1; and

FIG. 4 is a cross-sectional view taken along line 4—4 of FIG. 1.

As illustrated in FIGS. 2 and 4, the toggle bar operating assembly made in accordance with the present invention includes a shell 10 having a peripheral wall 11 comprising the opposing, longitudinally extending arcuate side walls 11a and 11b, an arcuate bottom wall 13, and an open top. The outer surfaces of side walls 11a and 11b are preferably convex and the inner surfaces concave while the upper surface of bottom wall 13 is concave and the lower surface is convex. Each of side walls 11a and 11b has a respective rectangular slot therein which is located approximately in the center of the side wall. Thus, wall 11a contains slot 14 therein and wall 11b contains slot 15 therein. In the preferred embodiment the slots are in alignment and the slots extend to the bottom edge of the respective side walls 11a and 11b.

The upper portion of side walls 11a and 11b are spaced apart a distance greater than the distance between the corresponding lower portion of the side walls on any one vertical plane to thereby define an inwardly projecting shelf 16. Shelf 16 is spaced between the top of slots 14, 15, and the top edge of wall 11 and extends circumferentially about the inner surface of wall 11. Shelf 16 forms a seat for the bottom surface of a jewel which is received through the open top, as described below.

The central portion of wall 13 is cut away thereby defining a central longitudinally extending opening 12 in bottom wall 13. The lateral edges of opening 12 contain notches therein, one of which is partially shown in FIG. 2.

Shell 10 is preferably formed from a unitary blank of metal which is optionally brass.

Longitudinally extending blade spring 34, having the respective apertures 35 and 36 at each end thereof, is seated within shell 10. The ends of blade spring 34 extend past central opening 12 with apertures 35 and 36 respectively overlying a different one of the notches in the lateral end edges of opening 12. As illustrated in FIGS. 3 and 4, the upper surface of blade spring 34 lies well below shelf 16 and the lower surface of blade spring 34 lies below the top of slots 14 and 15 and abuts a crossbar 28. Optionally, blade spring 34 will abut the inner surfaces of peripheral wall 11, but will be movable with respect thereto. The ends of shell 10 may be swaged over the ends of blade spring 34, as at 50 and 51, to maintain the blade spring in tension over crossbar 28.

A toggle 21 is in the form of a U-shaped yoke having an elongated shank portion 22 and a pair of spaced legs 23 and 24. Shank 22 is provided with notches 25 and 26, extending to the bottom of shank 22, for receiving a longitudinally extending fixed head 27 thereon, as shown in FIGS. 1 and 4. Head 27 may be connected to the shank in any conventional manner. A crossbar 28, which is optionally of square cross-section, extends between and is spaced from the ends of legs 23 and 24. The spacing between the legs is such that the ends of the legs straddle shell 10 when the crossbar is seated within slots 14, 15 of the respective shell side walls 11a and 11b.

A flexible closure strip 29, having the laterally extending projections 30 and 31 extending from approximately the middle of the respective longitudinal edges of closure strip 29, underlies crossbar 28. Closure strip 29 also includes the perpendicularly upwardly extending tabs 32 and 33 at the respective ends thereof. Closure strip 29 is secured in place in central opening 12 with tabs 32 and 33 engaged in the notches in the laterally extending edges of slot 12 and the ends of tabs 32 and 33 respectively passing through apertures 35 and 36 in blade spring 34 and being bent over blade spring 34 with

the ends of the tabs extending either toward or away from each other. FIG. 3 shows the tabs extending away from each other. Projections 30 and 31 underlie the respective slots 14 and 15 to add additional support and strength to the connection of the yoke and the shell. In the preferred embodiment of the present invention, the lower surface of strip 29 will be flush (i.e., coplanar) with respect to the lower surface of bottom wall 13.

Slots 14, 15, the adjacent portion of closure strip 29, projections 30 and 31, and the adjacent portion of blade spring 34 thus define a trunnion portion in which the crossbar 28 of the yoke is rotatably supported.

Closure strip 29 and blade spring 34 are optionally made of brass. However, blade spring 34 may be constructed to flex much more than the closure strip when the unit is rotated.

A jewel 37, having a flat lower face and convexly shaped upper face is sized and shaped to be received within the open top of shell 10 with the lower edges abutting wall 11 and the lower face seated upon shelf 16. Thus, the portion of peripheral wall 11 above seat 16 may be crimped over the surface of the jewel to maintain the jewel in place. Additionally, jewel 37 may be secured in place by any means well known in the art.

The assembly of blade spring 34 and closure strip 29 to the shell is such that the engagement of the blade spring with crossbar 28 places the blade spring under an initial bending stress as shown in FIG. 4. The engagement of tabs 32 and 33 with respective apertures 35 and 36 maintain the parts in pre-stressed assembled relationship. Additionally, the ends of blade spring 34 abut closure 13 (FIG. 4) and thereby exert an upward force on closure strip 29 through tabs 32, 33 to maintain the strip in place.

Sufficient clearance is provided between crossbar 28 and the walls of the respective slots 14 and 15 to permit the relative rotational movement therebetween. The opening between legs 23 and 24, crossbar 28 and the shank of the yoke is of sufficient size to permit the passage of the ends of the shell therethrough during the rotation of the yoke (or shell) about the aforementioned trunnion support. The action of blade spring 34 and closure strip 29 against the edges of the crossbar resiliently and frictionally resists any movement of the shell out of these positions in which the shell is parallel to or perpendicular to the yoke.

When in the proper assembled position with the cuff of a shirt-sleeve, the parts are disposed in the position shown in FIG. 1, with the cuff interposed between the movable head comprising shell 10 and fixed head 27. When it is desired to remove the cuff link shell 10 is rotated to a position in which the longitudinal axis of shell 10 is parallel to the axis of the yoke. In this position the shell 10 may easily pass through the openings in the shirt sleeves wherupon it may be rotated back to a position normal to the yoke.

Having described the preferred embodiment of my invention it will become obvious to those skilled in the art that modifications may be made therein without departing from the scope of the invention.

What is claimed is:

1. In a toggle finding for a jewel, a shell having an open top, and a peripheral wall sized and shaped to receive said jewel therein through said open top and having inward seat means for the reception of said jewel, said peripheral wall having opposing longitudinally extending sides having respective slots extending to the bottom edges of said peripheral wall, a bottom closure for said shell having a central longitudinally extending opening therein, a longitudinally extending blade spring within said shell below said seat means overlying and extending past the ends of said opening, a relatively flexible, longitudinally extending closure strip in said central opening having a bottom surface coplanar with the bottom sur-

face of said bottom closure, complementary fastening elements on said blade spring and said bottom closure for fastening said bottom closure to said blade spring, and a yoke having legs on each side of said shell and a crossbar extending between said legs, said bar substantially square in cross-section, said bar extending through said side slots and between and in turnable and resiliently clamped relationship with said blade spring and said closure strip.

2. In a toggle finding for a jewel, a shell having an open top, and a peripheral wall sized and shaped to receive said jewel therein through said open top and having inward seat means for the reception of said jewel, said peripheral wall having opposing longitudinally extending sides having respective slots extending to the bottom edges of said peripheral wall, a bottom closure for said shell having a longitudinally extending opening therein, a longitudinally extending blade spring within said shell below said seat means having an aperture adjacent each end thereof with the ends of said blade spring extending past the lateral edges of said opening, a relatively flexible, longitudinally extending closure strip in said opening having a bottom surface coplanar with the bottom surface of said bottom closure and having tabs at each end thereof respectively extended through said opening and the apertures in said blade spring and bent over said blade spring, and a yoke having legs on each side of said shell and a crossbar extending between said legs, said bar substantially square in cross-section, said bar extending through said side slots and between and in turnable and resiliently clamped relationship with said blade spring and said closure strip.

3. A toggle finding for a jewel as defined in claim 2, wherein the apertures in said blade spring overlie the lateral edges of said bottom closure opening.

4. In a toggle finding for a jewel, a shell having an open top, and a peripheral wall sized and shaped to receive said jewel therein through said open top and having inwardly projecting seat means spaced from the top edge of said peripheral wall for reception of the bottom of said jewel, said peripheral wall having opposing longitudinally extending sides having respective slots therein, the top edge of said slots being spaced below said seat means and the sides of said slots extending to the bottom edge of said peripheral wall, a bottom closure for said peripheral wall having a central longitudinally extending opening therein, a longitudinally extending blade spring within said shell having a bottom surface spaced below the top of said side slots with the ends of said blade spring extending past the ends of said central opening and having apertures therein adjacent each end of said blade spring, a relatively flexible longitudinally extending closure strip in said central opening having a bottom surface coplanar with the bottom surface of said bottom closure and having tabs respectively extended through said opening and said apertures and bent over said blade spring, and a yoke having legs on each side of said shell and a crossbar extending between said legs, said bar substantially square in cross-section, said bar extending through said side slots and between and in turnable and resiliently clamped relationship with said blade spring and said closure strip.

5. In a toggle finding for a jewel, a shell having an open top, and a peripheral wall sized and shaped to receive said jewel therein through said open top and having inwardly projecting seat means spaced from the top edge of said shell for reception of the bottom of said jewel in abutting relation thereto, said peripheral wall having opposing longitudinally extending sides having respective aligned slots extending to the bottom edge of said peripheral wall, a bottom closure for said peripheral wall having a central opening extending longitudinally past said side slots, a longitudinally extending blade spring within said shell below said seat means having ends extending past the ends of said central opening, said blade

spring having an aperture adjacent each end and being so positioned and sized as to overlie a different lateral edge of said bottom closure opening, a longitudinally extending flexible closure strip in said central opening having tabs extending into said shell through said apertures and bent over said flexible blade spring, and a yoke having legs on each side of said shell and a crossbar extending between said legs, said bar substantially square in cross-section, said bar extending through said side slots and between and in turnable and resiliently clamped relationship with said blade spring and said closure strip.

6. A toggle finding for a jewel as defined in claim 5, and portions of the peripheral wall adjacent the ends of

the blade spring being swaged over the ends of said blade spring to maintain said blade spring in tension over said crossbar.
